UNITED STATES PATENT OFFICE

1,950,730

WINDOW SCREEN

Charles P. Kegley, Pulaski, Va.

Application March 7, 1933, Serial No. 659,945

3 Claims. (Cl. 156—14)

The present invention contemplates a window screen intended to protect a single sash of an ordinary two-sash window, and provides as a means of attaching to said window a holding filler rail 5 of convenient width, the thickness of said holding filler rail corresponding to the width of the blind stop of a window, and its horizontal length being slightly less than the width of the interior window frame, measured between the exterior blind stops, said holding filler rail having slots 10 at either end, centrally and vertically to its cross-section; said slots fitting over finned rail holders secured to the inner faces of said exterior blind stops at a central point as regards their vertical 15 length, or directly opposite the union of the upper and lower window sashes; the fins on said rail holders being formed in such manner that one extends centrally and vertically from the securing base plate, and another horizontally from the 20 bottom of said securing base plate, said fins forming an inverted $\text{\texttt{T}}$ in cross-section; said holding filler rail being hinged at one horizontal edge to a half screen, said half screen being provided with a hook or fastener centrally positioned on the 25 interior lower frame member. This modified form has the advantage of being reversible, so that by sliding the slotted holding filler rail over the finned rail holders with the hinged edge upward, the attached screen section swings down- 30 ward to protect the lower window sash, and by sliding said holding filler rail over said finned rail holder with the hinged edge downward, said screen section swings upward to protect the upper sash, said lower screen section being provided 35 with means of securing to the window frame as heretofore set forth, and said window frame having eyes or complement parts to catch fasteners located at both top and bottom; said holding filler rail embodying the features of a holder and filler 40 strip between the exterior blind stops, and in conjunction with the lower horizontal fin of the finned rail holder, making the assemblage insect proof.

In the drawing forming a part of this specifica- 45 tion,

Figure 1 is a perspective view of the screen member of this invention.

Figure 2 is a cross-section of the upper part of a framed window, showing the modified or half 50 screen covering the upper window sash.

Figure 3 is a cross-section of the lower part of a framed window, showing the modified or half screen covering the lower window sash.

Figure 4 is a broken detailed perspective view 55 showing the finned rail holder attached to a blind

stop, and the holding filler rail and attached half screen in position to be slid downward, effecting a covering for a lower window sash.

Like marks of reference refer to like or corresponding parts, in which A is a window frame, B 60 is the holding filler rail, C is the half section screen, D is the finned rail holder, E is an upper window sash, and F is the corresponding lower sash. In Figure 1, holding filler rail B is attached to screen section C by hinges as at 1, butt hinges 65 being mortised into said holding filler rail B and said screen section C, as in Figure 4. Screen section C bears a hook or fastener 3, said hook or fastener engaging an eye or complement part 4, attached to the sill of said frame A. In Figure 1, 70 2 indicates the centrally disposed slots in either end of the holding filler rail E, said rail being shorter in horizontal length at either end than its attached screen section C by the outwardly fac- 75 ing width of blind stops 5, combined with the thickness of the attaching plate 6 of finned rail holder D; said slots being of a depth as to readily accommodate central vertical fin 7 of said rail holder D, the forked ends of said holding filler rail B resting on the lower horizontal fin 8 of said 80 rail holder.

It will be readily understood that while the inventor has indicated wooden screen frames, metallic frames would in no wise impair the efficiency of the present invention, nor does the inventor wish to limit his invention to the style of hinge illustrated and the manner of its attachment. It is further evident that this invention is not of necessity restricted to screening a window sash, but might be employed in the in- 85 stallation of ventilators, or like devices. Further, the present invention might profitably be altered in particular instances by providing two or more screen sections, hinged or fastened together by other means, to facilitate storage, han- 90 dling or installation, or for other meritorious purposes, and the inventor does not wish to limit his device to the illustrated form.

Advantages of the present invention, such as convenience of storage, handling and installation 100 from within a building through an open sash, without impairing the normal operation of the sashes either when in operative position or otherwise; the rigidity of the installation, the perfect closure of all insect entrances, and the manner 105 in which the screen may be swung outward without demounting when cleaning the exterior window sashes, are self-evident, as are the simplicity of manufacture and lack of skill required by a home owner or other person installing screens 110

made in the manner of this invention.

Having, therefore, described my invention, what I claim as new, and desire to protect by Letters Patent, is:

3. 1. In an article of the nature set forth, the combination of a half screen, a holding filler rail shorter at either end than the width of said half screen to which it is hinged by the thickness of the outer blind stops of a window frame, said holding filler rail being slotted centrally and vertically at either end to engage rail holding clips affixed to said exterior blind stops.
10. 2. In an article of the nature set forth, the combination of a half screen or hinged sectional equivalents, a holding filler rail shorter at either end than the width of said half screen to which it is hinged by the thickness of the outer blind stops of a window frame, said holding filler rail being slotted centrally and vertically at either end, and finned rail holders capable of attachment to the inward faces of said outer blind stops, said rail holders having central fins pro-

jecting centrally and vertically from the attaching base to engage the slotted ends of said holding filler rail.

3. In an article of the nature set forth, the combination of a half screen or hinged sectional equivalents, a holding filler rail shorter at either end than the width of said half screen to which it is hinged by the thickness of the outer blind stops of a window frame, said holding filler rail being slotted centrally and vertically at either end; finned rail holders capable of attachment to the inward faces of said outer blind stops, said rail holders having fins projecting centrally and vertically from the attaching base to engage the slotted ends of said holding filler rail, and secondary fins projecting horizontally from the bottom of said attaching base, forming an inverted T in combination with said central vertical fins, said secondary horizontal fins forming a seating surface for the forked ends of said holding filler rail.

CHARLES P. KEGLEY.
